STOVE TRIMMING

Filed July 15, 1922

2 Sheets-Sheet 2

UNITED STATES PATENT OFFICE.

ALVIN G. SHERMAN, OF DETROIT, MICHIGAN, ASSIGNOR TO DETROIT VAPOR STOVE COMPANY, OF DETROIT, MICHIGAN, A CORPORATION OF MICHIGAN.

STOVE TRIMMING.

Application filed July 15, 1922. Serial No. 575,317.

To all whom it may concern:

Be it known that I, ALVIN G. SHERMAN, a citizen of the United States, residing at Detroit, in the county of Wayne and State 5 of Michigan, have invented certain new and useful Improvements in Stove Trimmings, of which the following is a specification.

This invention relates to trimming for stoves. It is the object of the present invention to provide a trimming and corner strip construction for stoves which will give a plain rounded effect and be extremely artistic by reason of its simplicity and entire elimination of exposed bolts or other fastening devices.

In the drawings,—

Fig. 1 is a perspective of the upper portion of a stove provided with this improved trimming.

20 Fig. 2 is a section on the line 2—2 of Fig. 1.

Fig. 3 is a section on the line 3—3 of Fig. 1.

25 Fig. 4 is a section taken on the line 4—4 of Fig. 3.

Fig. 5 is a section on the line 5—5 of Fig. 3.

It will be unnecessary to describe the various parts that go to make up a gas or 30 vapor stove as these are thoroughly apparent from the drawings.

Along the top side corners of the oven are a pair of trimming strips *a* and *b*. At the end of the shelf *c* is a third trimming strip *d*. 35 These strips are preferably pressed steel parts that are nickle plated and buffed. They are rounded as plainly shown in Figs. 1, 2 and 3, giving a clean, simple appearance that makes for artisicness. Furthermore, they give a rounded corner for the stove which makes it easy to keep clean.

Specifically considered, these strips are more or less rounded in cross section. The strip shown in section in Fig. 3 approximates a segment or a quarter circle while that portion of the strip that runs back along the shelf *c* and joins the shelf *c* with the top of the oven has a curvature of a very much larger radius and approximates a straight 40 line.

The special features are a rounded channel on the inside to which is welded or otherwise secured the bolts *e*. The sheet metal plates which form the adjoining surface are 45 off-set as at *f* to give a jog. Where the join-

ing plates are joined at a right angle as shown in Fig. 3, slightly beyond the jog, the plates are bent to a substantially 45° angle and overlapped. The bolts *e* pass through the registering perforations in the 50 overlapped portions and these are tightly secured together with the nuts *g*.

In the joint shown in Fig. 2, the plates meet in a straight angle and beyond the jog they are turned down at a right angle and 55 overlapped as shown at *h*. A stove bolt *i* is then passed through these opposite portions and through the side wall *j* of the oven to unite the two together. The bolt *k* is welded to the inside of the trimming and 60 passed through one of the plates underneath the trimming and is secured thereto by the nut *m*. This secures the trimming indirectly to both plates. The jog in both plates brings the edges of the trimming substantially flush 65 with the plates or sheets and the trimming fits into the jogs so that when the nuts are tightened up they draw the trimming snugly into place. This makes a very neat and 70 sanitary joint.

What I claim is:—

1. In stove construction, the combination of a pair of sheets of metal secured together, a trimming strip secured above the joint of the two sheets, and concealed fastening devices anchored to the inside of the trimming strip for fastening the trimming strips to the sheets of metal.

2. In stove construction, the combination of a pair of sheets of metal overlapped, 90 means for securing the overlapped portions together, a trimming strip secured on the outside of the joint between the sheets of metal and concealed fastening devices anchored on the inside of the trimming strip 95 for securing the trimming strip to the sheets of metal.

3. In stove construction, the combination of a pair of sheets of metal joined together, means for securing the same together, a 100 trimming strip having bolt heads secured to the inside of the trimming strip and bolt stems projecting inwardly therefrom, said trimming strips secured on the outside of the joint between the two sheets of metal, 105 and a nut run on to the stem of the bolt for securing the trimming strip to the sheets of metal.

4. In stove construction, the combination of a pair of sheets of metal having their 110

meeting portions offset to form jogs and secured together, a trimming strip engaging between the jogs to the outside of the joint between the sheets of metal, and concealed means for securing the trim strip in such position.

5. In stove construction, the combination of a pair of sheets of metal having jogs therein and overlapped edges thereto to form 10 a joint, means for securing the overlapped portions together and a trimming strip for engaging between the jogs at the joint, and concealed means for securing the trimming strip to the overlapped sheets of metal.
- 15 6. In stove construction, the combination of a pair of sheets of metal having jogs near their meeting edges, and having their meeting edges overlapped, means for securing the overlapped edges together, and a 20 rounded trimming strip having bolts with bolt heads welded to the inside of the strip and engaging between the jogs, at the joint, and a nut threaded on to the stem of each bolt for securing the trimming strip to the 25 sheet metal members.

7. In stove construction, the combination of a pair of sheets of metal having jogs in their meeting edges, a rounded trimming strip arranged to fit snugly into the jog 30 substantially flush with the main portions of the sheets of metal at each edge of the trimming strip, means for securing the sheet metal members together and concealed means secured to the inside of the trimming 35 strip for drawing the trimming strip tightly to the sheet metal members at the joint and holding same there.

8. In stove construction, the combination of a pair of sheets of metal having jogs near 40 their meeting edges and overlapped together between the jogs, bolts and nuts for securing same together, a rounded trimming strip having bolts with their heads secured to the inside of the trimming strip with the stem

of the bolt passing through one or more of 45 the sheets of metal, and a nut on the stem of the bolt for drawing the rounded trimming strip down into the jogs with the outside surface of the trimming strip substantially flush at its edges with the main portions of 50 the sheets of metal.

9. In stove construction, the combination of an oven top and an oven side and a shelf construction, the last mentioned member being of less width than the former two and 55 situated at the rear thereof, the oven top and the shelf being bent into overlapping relation with the top of the side wall of the oven, means for securing these members together, a trimming strip comprising a 60 rounded strip that fits over the joint between the oven top and oven side at the front, and which fits over the joint between the oven top, the oven side, and the shelf at the rear, and concealed means for holding said trim- 65 strip in place.

10. In stove construction, the combination of an oven top and oven side, and shelf, the last mentioned member being narrower than the two preceding members and being located at the rear thereof, the said oven top and shelf having turned over angular portions overlapping the top of the side of the oven, means for securing same together to form a joint, a trimming strip having a 70 relatively rounded channel portion at the front that fits over the joint between the oven top and side and having a shallower rounded portion that fits over the joint between the oven top, oven side and shelf at 75 the rear, bolts, and nuts run on the bolt stems for securing the trimming strip tightly to the said meeting members, some of the said fastening devices being welded to the back of the trimming strip. 80 85

In testimony whereof I affix my signature.

ALVIN G. SHERMAN.
